LEOPOLD KLEE, OF PITTSBURG, PENNSYLVANIA, ASSIGNOR TO HIMSELF
AND CHARLES T. HERROSEE, OF SAME PLACE.

Letters Patent No. 78,973, dated June 16, 1868.

IMPROVEMENT IN MASH-TUBS.

The Schedule referred to in these Letters Patent and making part of the same.

TO ALL WHOM IT MAY CONCERN:

Be it known that I, LEOPOLD KLEE, of Pittsburg, in the county of Allegheny, and State of Pennsylvania, have invented a new and useful Improvement in Mash-Tubs; and I do hereby declare that the following is a full, clear, and exact description thereof, which will enable others skilled in the art to make and use the same, reference being had to the accompanying drawings, forming part of this specification, in which—

Figure 1 represents a vertical sectional elevation of my improved mash-tub.

Figure 2 represents a plan of the cover.

Figures 3 to 5 represent modifications of my improvement.

Similar letters of reference indicate corresponding parts.

The nature of this invention relates to improvements in mash-tubs for preparing mash for brewing and other purposes, whereby it is designed to provide a more improved tub for the purpose than those now in use.

It consists in the combination of two vessels, one within the other, having a space between them.

Also in the arrangement of a cover, common to both, arranged so as to hermetically seal the interior of the tub and the space between the two parts.

Also, in an arrangement of means for introducing steam or other heating-medium to the interior, and also to the space between the two parts for heating the mash.

Also, a provision of means for the application of compressed air to the mash, to facilitate the preparation of the mash and discharge of the product.

Also, in several combinations hereinafter specified, and

Also, in several modifications of some of my improvements, as will be more fully described on reference to the accompanying drawings.

The want of a more perfect apparatus for mashing is being felt by all engaged in the manufacture of fermented liquors, for the reason that those now in use give to the operator no means of controlling the temperature in the same, thus endangering the result of the process by a far greater chance of introducing the ruinous lactic acid, and to avoid these defects is the object of my invention.

My invention is also designed to provide a mash-tub that may be readily opened or hermetically closed, and that may be heated from all the exterior portions, as well as to introduce the heat into the same above the mash, and from which the wort and the grains may be discharged through the bottom with great facility.

A represents an outer tub, constructed preferably of wood, and B represents an interior iron or other suitable sheet-metal tub, which is arranged within the outer tub in a manner to provide a space, C, around and under the inner metal tub.

The upper end of the wood tub A is provided with a groove, into which a flange turned over from the top of the metal tub may be arranged to fit tightly, and a joint, b, of metal tubing may be united to the top of the tub B, and provided with a flange, C, resting on the top of the tub A.

D represents a cover of wood, made in three parts, the middle portion being permanently secured to the top, and the parts D¹ and D² are hinged to it. The joints between the several parts are packed with rubber, or other suitable packing, d, and a strip of similar packing is secured to the under outer face of the cover, where it bears upon the top of the tub.

e represents clamps, whereby the cover is secured to the flange of the metal tub, so as to constitute a hermetically-tight joint, and the flange a of the metal tub is fitted hermetically in the groove of the tub A.

The movable portions D¹ and D² may be raised for filling the tub, or for effecting a passage into it for any purpose.

E represents a steam-pipe, provided with the branches E¹ and E², for conveying steam into the space C.

F represents a man-hole opening into the bottom of the metal tub through the wood bottom of the tub A,

for cleaning out the grain. It is provided with a wood plug, *f*, and a metal cap, *f'*, and tightened up in a suitable manner by a set-screw, and elastic or other suitable packing.

G represents a pipe for drawing off the wort after it has been filtered through a strainer, arranged over the mouth of the pipe in the bottom of the tub *B*.

H represents a pipe for drawing off the water resulting from condensation in the space *C*.

I represents an air-pump, arranged upon the top of the tub for compressing the air in the tub, to facilitate the operation of preparing the mash and assist the separation and filtration of the wort, after the mashing process has been completed.

The apparatus for stirring the mash may be operated in any suitable manner from a shaft passing through the stationary portion *D* of the cover, or from the side of the tub.

In fig. 3 I have shown a modification of the means of attaching the cover. Instead of placing it on the top and providing for obtaining ingress into the tub by a hinged portion of the same, I have provided for fitting the edge of the cover into the channel in the upper end of the wood portion of the tub, wherein the flange *a* of the metal tub is fitted, effecting the tightening of both joints by the hoops of the wood tub, and I provide for entrance into the tub by the man-hole *K* in the cover.

Figs. 4 and 5 represent another modification, wherein the cover is made whole, and rests upon the top of the tub, and is secured thereto by clamps, as in fig. 1. In this example I have provided for obtaining access to the tub by raising the cover from it by cords and pulleys, which may be suspended from the beams above the tub. When this method of opening is adopted, the stirring-apparatus may be operated from the side, as shown in red in fig. 5.

It will be seen that by means of the arrangements above described access may be readily had to the interior, while the washing process is being effected; also that the operation of charging the tub through the top and discharging through the bottom, may be effected without inconvenience from the steam or hot water; also that the heating of the mash may be more readily effected by the application of the steam around the exterior surface of the metal tub, and upon the surface of the mash within the same; also, that by reason of the hermetical joints, the heating may be more rapidly effected, and the pneumatic pressure may be applied whenever necessary to drain or exhaust the wort from the grains, which may thereby be effected within such given time as may be deemed necessary by the operator. Also, that by means of the arrangements described the process of converting the starch into sugar (the temperature of which process lies within the limits of few degrees) is rendered sure, safe, and controllable by the operator, and for these very reasons all danger of the formation of that greatest of all enemies the brewer has to contend with, the pernicious lactic acid, is infallibly prevented.

Having thus described my invention, I claim as new, and desire to secure by Letters Patent—

1. The combination of the tub *A* with the tub *B*, when constructed and arranged, substantially as and for the purpose described.
2. The combination, with the tubs *A* and *B*, of a cover, when arranged to hermetically close the openings to both tubs, substantially as and for the purpose described.
3. The combination, with the tubs *A* and *B*, of the heating-pipe *E*, when arranged substantially as and for the purpose described.
4. The combination, with an hermetically-closed mash-tub, substantially such as herein described, of a means for compressing the air therein, as and for the purpose described.
5. The combination, with the mash-tubs *A* and *B*, of a hinged cover, *D*, when arranged to be hermetically secured to the tubs, substantially as and for the purpose described.
6. The combination, with the mash-tubs *A* and *B*, of the cover, when arranged to hermetically close the same, as shown in fig. 3, substantially as and for the purpose described.
7. The combination, with the tubs *A* and *B*, of the man-hole appliances *F*, pipes *G* and *H*, when all constructed and arranged substantially as and for the purpose described.

LEOPOLD KLEE.
